[57] **CLAIM**

The ornamental design for an eyewear front, as shown and described.

DESCRIPTION

FIG. 1 is a front elevational view of an eyewear front showing my new design;

FIG. 2 is a front perspective view thereof;

FIG. 3 is a rear elevational view thereof;

FIG. 4 is a top plan view thereof;

FIG. 5 is a side elevational view thereof, the side opposite being a mirror image; and,

FIG. 6 is a bottom plan view thereof.

The broken lines appearing in FIGS. 1-6 are for environmental purposes only and form no part of the claimed design.
